KNITTING MACHINE FOR MAKING GLOVE FINGERS

Charles H. Usher, Chicopee Falls, Mass., assignor to Lamb Knitting Machine Corp., Chicopee Falls, Mass., a corporation of Massachusetts

Application December 31, 1937, Serial No. 182,835

2 Claims. (Cl. 66—65)

This invention relates to improvements in knitting machines of the type known as glove fingering machines. In such a machine, a pre-knitted hand of a knitted glove is inserted in the machine and the fingers knitted thereon. In the machine under consideration here, each finger is knitted separately, a tube of yarn of suitable diameter being knitted on the hand at the proper point and then formed into a finger by closing the end of the tube.

It is necessary to rethread the machine and reinsert the glove being processed each time a finger is to be added; also, the machine often becomes "snagged," necessitating removal of the carriage from the bed in order to unravel the tangle of yarn. These operations seriously hamper production, by tying up the machine until the necessary adjustments or alterations are made. It is, therefore, the purpose of this invention to provide a glove fingering machine which has been so constructed as to increase the availability of the machine for work by cutting to a minimum the time consumed in starting each finger or in removing tangled threads if the yarn becomes snagged.

The particular features which enable me to accomplish this purpose with my invention will appear more fully by a consideration of the specification read in conjunction with the drawings in which—

Fig. 1 is a front view of the glove fingering machine;

Fig. 2 is an end elevation of the machine of Fig. 1; and

Fig. 3 is an enlarged detail of the mounting for the connecting rod on the carriage.

Referring to Figs. 1 and 2, the knitting machine consists of a reciprocable carriage 1 sliding on ways 2 over a bed 3. The bed 3 carries 40 needles 4 which are reciprocated to perform the knitting operation by cams carried on the carriage 1. This operation and the construction to carry it out are well known in the art and will not, therefore, be further described. The thread 45 5 passes from a suitable tensioning device, not shown, down through an eye 6 to the bed 3 where the knitting takes place. The carriage likewise carries guard members 7 and 9 to keep the eyes of the needles open as they reciprocate from their lowest position, one guard 7, located at the 50 front of the carriage, being a simple gooseneck member and the other, 9, being a brush held by a gooseneck clip. It is not necessarily mandatory that the guard members 7 and 9 be of different construction, the particular form illus-

trated being merely one embodiment. The preceding construction is well known in the knitting machine field and, therefore, will not be described further.

As was explained earlier, the machine must be 5 rethreaded and the glove reinserted each time a finger is started. To do this successfully, the carriage has to be operated manually and slowly for the first few reciprocations. After the finger is started, the machine can be mechanically 10 driven until the necessary finger length has been knitted. By means about to be explained, I have provided for both manual and mechanical operation with the operating mechanism for both 15 types of operation located at the back of the machine away from the carriage with the parts arranged so that the operator can readily control the machine both during rethreading and knitting.

Referring to Figs. 1 and 2, reciprocation of the 20 carriage 1 is provided by a crank arm 10 and a connecting rod 11, the latter member being pivotally connected as at 13 to the carriage 1. Crank arm 11 is pinned to a shaft 12 which is supported in bearings on the end of gooseneck 25 extensions 15 of the frame of the machine. A pulley 17 is pinned to the shaft 12 and connected by belt 18 and a foot-controlled friction clutch not shown to a suitable rotating shaft. Crank arm 11 also has a handle 19 mounted on one end 30 whereby the carriage 1 can be reciprocated manually if it is so desired. Thus, during the rethreading operation the operator, standing at the left of the machine as shown in Fig. 2, can move the carriage manually by handle 19, and 35 then he can provide for continuous operation by working his foot controlled friction clutch and by the belt driven pulley taking over the driving work during the rest of the knitting operation. Particularly is it to be noted that during the 40 continuous operation, the rotating parts are at the back of the machine away from the operator, which reduces the danger of injury to a minimum and provides clear view of the knitting operation.

Often during the knitting operation, the yarn snarls, and the operator must stop his machine to untangle the strands. By the construction described below, the operator can separate the carriage and bed without disconnecting the driving means, and can very easily gain accessibility to the needles carried by the bed, with a minimum of time wasted.

Referring to Fig. 3, connecting rod 11 is threaded at the carriage end and passes through a two-

45

50

55

piece collar 20 mounted in the pivot 13 which is suitably journaled in a boss 21 built out from the carriage. The length of the connecting rod 11 necessary for proper reciprocation of the carriage is determined and the rod locked in position by nuts 21 and 22 which bear on washers 24 and 25. The two-piece collar 20 is mounted through the width of the pivot 13, see Fig. 3, so that with the nuts 21 and 22 in position, the connecting rod 11 can turn around its longitudinal axis. Thus, the mounting at the carriage end not only allows the connecting rod to have a wrist pin motion by means of pivot 13, but also a twisting motion by reason of two-piece collar 20.

Referring again to Figs. 1 and 2, the ways 2 consist of rods passing through bosses 26 in the frame of the machine and are secured in position by taper pins 27. Thus, as is shown in Fig. 2 by the dotted position of the parts, if the pins 27 in the front way 2 are removed the rod may be removed and the carriage rotated to its dotted position where there is free accessibility to the bed mechanism. During the swinging of the carriage on the right way 2 (see Fig. 2), the pivot 13 drops down and twists slightly around the connecting rod 11, but due to the type of connection between the pivot 13 and the connecting rod 11, there is no difficulty and the connecting rod need not be disconnected from the carriage. In this manner the bed of the knitting machine is made accessible for the operator to untangle yarn and at the same time the machine need not be disassembled or its alignment disturbed.

Having disclosed my invention, what I claim is:

1. In a glove finger knitting machine having a carriage for reciprocation over a needle-carrying bed, a pair of ways of circular cross-section for

supporting said carriage, at least one of said ways being releasably secured to the frame of the machine, in combination with a crank operated connecting rod for reciprocating said carriage, said rod being pivoted at a point closely adjacent one of said ways at one end of the carriage, said pivot providing for both wrist-pin action and rotational twist of the connecting rod whereby when the way remote from the connecting rod pivot is removed the carriage may be rotated about the adjacent way at right angles to the plane of reciprocation without disconnecting the connecting rod at the pivot.

2. In a glove finger knitting machine, the combination of a needle-carrying bed, a carriage mechanism for reciprocation over the needle-carrying bed so as to work the needles, a pair of ways for supporting said carriage mechanism, means to tip said carriage mechanism up and back while supported on one of the ways, so as to give access to the needle-carrying bed and the under part of said mechanism from the front part of the machine, a power shaft mounted at one side and back of that way which supports the carriage mechanism, a hand crank on the end of said power shaft and in approximately the vertical plane of said carriage way last mentioned, a connecting rod between said crank and the carriage and pivoted on the carriage just above the last mentioned carriage way, a power driving connection on said shaft in addition to the hand crank, all constructed and arranged to give easy access to the whole mechanism without interference from the hand and power driving means.

CHARLES H. USHER.
